REMOVABLE CAR BED

Harold Gevertz, San Francisco, Calif.

Application July 15, 1957, Serial No. 46,928

Term of patent 3½ years

(Cl. D5—5)

The figure is a perspective view of a removable car bed, showing my design.

The dominant feature of my design resides in those portions shown in full lines on the drawing.

The side and end opposite from those shown in the drawing are the same as those depicted.

I claim:

The design for a removable car bed, as shown and described.
